US0D1059273S

(12) **United States Design Patent** (10) **Patent No.:** **US D1,059,273 S**
(45) **Date of Patent:** **** Jan. 28, 2025**

(54) **PORTABLE POWER SUPPLY**

(71) Applicant: **Shenzhen Grandpower New Energy Development Co., Ltd**, Shenzhen (CN)

(72) Inventor: **Fan Zhou**, Hubei (CN)

(**) Term: **15 Years**

(21) Appl. No.: **29/863,966**

(22) Filed: **Dec. 25, 2022**

(51) **LOC (15) Cl.** **13-02**

(52) **U.S. Cl.**

USPC **D13/110**

(58) **Field of Classification Search**

(57) **CLAIM**

The ornamental design for a portable power supply, as shown and described.

DESCRIPTION

FIG. 1 is a perspective view of the portable power supply showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof when a charging power cord is pulled out.

1 Claim, 8 Drawing Sheets
